CLAIM

The ornamental design for a pet chew, as shown and described.

DESCRIPTION

FIG. 1 is a top view of my new design, a pet chew.

FIG. 2 is a front elevation view of my design.

FIG. 3 is a bottom view of my design.

FIG. 4 is a right side elevation view of my design.

FIG. 5 is a rear elevation view of my design; and,
FIG. 6 is a left side elevation view of my design.
The broken lines in the drawings illustrate portions of the pet
chew that form no part of the claimed design.
